Patented Oct. 7, 1913.

UNITED STATES PATENT OFFICE.

ISAAC SNOW, OF LAWRENCE, MASSACHUSETTS, ASSIGNOR OF ONE-HALF TO HARRY CLOUGH, OF LAWRENCE, MASSACHUSETTS.

THREADING DEVICE FOR SHUTTLES.

1,074,987.

Specification of Letters Patent.

Patented Oct. 7, 1913.

Application filed January 10, 1913. Serial No. 741,294.

To all whom it may concern:

Be it known that I, Isaac Snow, a citizen of the United States, residing at Lawrence, in the county of Essex and State of Massachusetts, have invented certain new and useful Improvements in Threading Devices for Shuttles, of which the following is a specification.

My invention relates to threading devices 10 for shuttles of the type wherein the shuttle can be threaded either by hand or by the operation of an automatic loom without the use of suction.

My invention is intended especially for 15 use as an automatic threader. In such a device, the passing of the shuttle back and forth across the loom carries the filling into the shuttle eye.

The advantages of my device are its cheapness as it is made of substantially one piece 20 of metal and may readily be stamped and formed into shape, and the fact that the filling when once it has got into place in the shuttle eye cannot unthread. It may be made of sheet metal and is therefore much 25 lighter, stronger and cheaper than a casting.

In the drawings, Figure 1 is a plan view 30 of the front or eye end of the shuttle with one form of my device in place. Fig. 2 is an elevation from the right or eye side of the shuttle, parts being broken away to show the construction. Fig. 3 is a sectional elevation from the front on line X—Y of Fig. 1. Fig. 4 is a sectional elevation from the back on 35 line O—P of Fig. 1, part of the bobbin being broken away. Fig. 5 is an elevation of my threader removed from the shuttle the same as seen from the right. Fig. 6 is a sectional elevation as seen from the left 40 on line M—N of Fig. 4. Figs. 7, 8, 9, 10 and 11 are sectional elevations of modified forms of my device seen as from the back or from the bobbin recess on a line such as O—P of Fig. 1, with the bobbin omitted.

45 A represents the wood of the shuttle, B the bobbin and C the bobbin recess.

E represents a recess cut into wood A which for convenience I will call the threader recess. This threader recess E comprises 50 four parts. First, the portion 18 which is cut to fit the threader proper F and which at 60 and 61 is cut away to receive ears 33 and 34. This portion 18 is formed to receive and closely fit the bottom 30 of the 55 threader and the sides 31 and 32. Second,

the neck 19 which is almost directly in front of the end of bobbin B and is so formed that it makes a shoulder with portion 18 and registers with the inside of threader F at the bottom. Third, the portion 20 of the threader recess which continues forward from the bottom 30 of threader F sweeping upward to a point at the right of and near the metal tip of the shuttle. The end of this portion 20 is somewhat below the level 60 of the top of the shuttle on account of the tapering point thereof. The portion 21 of threader recess E forms a sort of ledge beginning at the left front portion of the bobbin recess and continuing forward on a level 65 with the top of ear 33 substantially on the same level along the side of threader F as shown. It is recessed at the side to receive threader F. The bottom of portion 21 is 70 substantially level and it as well as its outside wall are close to the tip of the top guide plate of the threader. As shown in Fig. 3, the portion 20 next the shuttle eye is perpendicular and at its bottom slopes up to the edge of ledge 21.

A slot 22 is cut through the wood on the right of the shuttle and enters the portion 18 of the threader recess. This slot enters an eye 23 cut in the wood. At the top and 75 ends, slot 22 is suitably rounded and smoothed so that the filling will have no chance to catch anywhere.

The body or barrel of threader F at the bottom 30 is of semi-cylindrical form while the side walls 31 and 32 continue straight 80 upward for a certain distance. An ear 33 is bent outward on one side and another ear 34 on the other side to rest in recesses 60 and 61 cut into the wood on each side of the threader recess E. Screws 65 and 63 85 pass through suitable holes in each ear 33 and 34 into the wood A of the shuttle and hold threader F in place. The top edge 35 of side 31 is preferably so formed as to curve from each end upward and to just 90 pass inside the depending tip 37 of a top guide plate 36 which is an extension of side 32 bent over so that it slopes down and to the left as shown in Fig. 4. The back edge 51, nearest bobbin B, of top guide plate 36 95 has a long slope as shown in Fig. 1, while the front edge 50 slopes slightly backward in line with slots 38 and 22. The slot 38 in the side 32 when the parts are in place 100 adjoins the inner end of slot 22 in the wood of 105 110

the shuttle and slopes back as does slot 22 until it connects by a change of direction with the eye 39 of the threader F at the forward edge thereof. This eye 39 registers 5 with the eye 23 in the wood when the parts are in place. The top edge 35 of side 31 is preferably curved upward from the end of ear 33 to its high point inside of tip 37 thence down again to the level of the bottom 10 tom of ledge 21 of threader recess F. The outside of the top edge 35 is preferably rounded or beveled as shown in Figs. 3 and 4.

It will be observed that if the filling K should start at the center of the end of bobbin H, it would be below and to the right of the tip of the top guide plate 36 which forms a hook 37. When in place passing through eyes 39 and 23, the filling will pass through the eyes 39 and 23 bearing against 15 the pins 43 and 44 which I prefer to drive through the eye 23 in the wood.

If a bobbin is used which is wound as shown in Fig. 1 in such a direction that when the filling K unwinds, it passes under 20 the end of the bobbin from left to right toward the shuttle eye, and the filling is drawn forward, it is carried with a sweeping action in a direction which will carry it underneath the tip or hook 37. When it 25 once catches under hook 37, it cannot escape. If the filling is then drawn back and to the right, it is drawn along the front edge 50 of top plate 36 down through slots 23 and 38 into the shuttle eyes.

30 35 In an automatic loom, the end of the filling K is fastened to a stationary part D in front of where the front of the shuttle will be when a new bobbin is inserted in the shuttle. When inserted, the bobbin and shuttle 40 are thrown across the lay causing the filling to run out in a well known manner. As it runs out, the filling slips along the back edge 51 of top guide plate 36 and as this guide plate slopes downward to the left, 45 it slips over the end of tip 37 under the point thereof. This travel of the filling is caused, as will be seen by examining the full line in Fig. 2, by the tendency to straighten the bend in the filling and by 50 reason of the sweeping or bellying action as it unwinds around the end of bobbin B.

After it is once under tip 37 on account of the curved shape of the top edge 35 of side 31, it tends to straighten and therefore to 55 slip up and over the top thereof, as shown by the dotted lines in Figs. 4 and 6 finally landing in the barrel of the threader. When the shuttle is returned, the filling K has been held by the shifting of the warp threads 60 close to the cloth on the other side of the loom so that it is pulling in the opposite direction whereby as the filling runs out, it is dragged along the front edge 50 of top guide plate 36 and sinks naturally through 65 slot 22 in the wood and slot 38 in the metal

into the eyes 23 and 39. Slot 38 preferably makes a sharp turn as shown in Fig. 5 which tends to prevent the filling from slipping back through the slot or unthreading.

In Figs. 7, 8, 9, 10 and 11, I show different forms of my threader. In Fig. 7, top guide plate 70 slopes down to the left and has no hook whatever but merely passes beyond the side wall 71 into a recess 72 corresponding to portion 21 shaped from the 75 threader recess in the wood B of the shuttle, as shown.

In Figs. 7, 8, 9, 10 and 11, I show a plate 93 inserted through the side of the threader and cut away at its bottom 41 to serve as a guide for the filling from the bobbin to the shuttle eye, and to keep the filling near the center of the bobbin as it runs out. In Fig. 8, the top guide plate 73 is level and terminates in a hook 74 while the side wall 75 is bent inward to form a hook 76. This gives two hooks 74 and 76 to prevent the filling from escaping. In this form, the top guide plate 73 at its back edge is beveled downward and to the left, as shown at 77. 90 In Fig. 9, the top plate 78 slopes up to the left and terminates in a square hook 79 which passes beyond the side wall 80 into a recess 81 corresponding to portion 21 shaped from the threader recess in the wood H. Fig. 10 shows a construction which may be used with a bobbin which is wound either to the right or to the left. The top guide plate 90 is the same as 36 and the shape of the bottom and sides is the same. The wall on one side 91 is extended at the back and bent at right angles as shown at 92 to form a deflector plate which is curved over and down to a point above the cut away portion 41 of the inserted plate 93. The 105 other wall 94 is extended backward and is bent toward the deflector plate and is provided with saw teeth 95 which rake downward. The result of this construction is that the deflector plate 92 tends to direct the filling downward toward teeth 95 and when once caught therein it is held until it either drops to a lower tooth or catches under the hook 96 in which top plate 90 terminates. 110

In Fig. 11, I show a construction similar 115 to Fig. 10 except that the deflector plate 98 which corresponds with plate 92 is also provided with teeth 99 which rake downward so as to coöperate with teeth 95.

The principal features of my invention 120 are the threader proper formed preferably of substantially one piece of sheet metal with a horizontal barrel of semi-cylindrical form and with vertical side walls in one of which is a slot leading into an eye, that side being extended upward and bent over beyond the top edge of the other vertical side wall of the threader. This other side wall may or may not be curved and may assume various forms at its top edge to coöperate with the 125 130

tip of the top guide plate. The top guide plate slopes forward and away from the shuttle eye on its back edge and backward toward the shuttle eye on its forward edge.

5 For an automatic shuttle, the top guide plate should also slope downward especially at its back edge and to the left. With a hand threader, the construction shown in Fig. 9 may be used. The wood of the shuttle 10 is cut away adjoining, below and forward from the tip of the top guide plate opposite the shuttle eye so as to receive the filling and allow it to swing under the tip. The wood of the shuttle may be cut away to form a 15 slot and eye which coöperate with the slot and eye in the metal of the threader. The tip of the top guide plate on the side opposite the shuttle eye may be bent downward into various forms of hooks and the top 20 edge of the adjoining side wall may be bent into a hook if desired. To accommodate bobbins wound in the reverse manner, the side wall of the threader at the back nearest the shuttle eye may be bent inward and cut 25 in a downward curve with or without downwardly raking teeth so as to form a deflector plate to direct the filling over and down toward the other wall which may be provided with downwardly and inwardly raking teeth.

30 What I claim as my invention and desire to cover by Letters Patent, is:

1. In a shuttle, the combination of a wooden body having a bobbin recess and a 35 threader recess from which a slot and eye extend through the side, with a threader which fits into the threader recess and which has a barrel and vertical side walls, of which the side wall adjoining the shuttle eye has a 40 slot which connects with an eye both of which register with the slot and eye in the wooden body and said side wall being extended upward and bent over beyond the top edge of the other side wall forming a 45 top guide plate which slopes from the back forward away from the shuttle eye and from the front backward to a point adjoining the slot in the threader, and means for fastening the threader in place as described.

50 2. In a shuttle, the combination of a wooden body having a bobbin recess and a threader recess from which a slot and eye extend through the side, with a threader which fits into the threader recess and which 55 has a barrel and vertical side walls of which the side wall adjoining the shuttle eye has a slot which connects with an eye both of which register with the slot and eye in the wooden body said side wall being extended 60 upward and bent over forming a top guide plate which slopes from the back forward away from the shuttle eye and from the front backward to a point adjoining the slot in the threader, said top guide plate terminating in a hook which extends over and

beyond the top edge of the other side wall which is curved from each end upward toward a point adjoining said hook and is beveled on the outside, and means for fastening the threader in place as described. 70

3. In a shuttle, the combination of a wooden body having a bobbin recess and a threader recess formed to receive a threader and extended forward from the bottom and which has a longitudinal ridge on one side 75 and connects on the other side with a slot and eye which extend through the side, with a threader which fits into the threader recess and which has a barrel and vertical side walls of which the side wall adjoining the 80 shuttle eye has a slot which connects with an eye both of which register with the slot and eye in the wooden body and said side wall being extended upward and bent over beyond the top edge of the other side wall 85 forming a top guide plate which slopes from the back forward away from the shuttle eye and from the front backward to a point adjoining the slot in the threader, and means for fastening the threader in place as 90 described.

4. In a shuttle, the combination of a wooden body having a bobbin recess and a threader recess from which a slot and eye extend through the side, with a threader 95 which fits into the threader recess and which has a barrel and vertical side walls of which the side wall adjoining the shuttle eye has a slot which connects with an eye, both of which register with the slot and eye in the 100 wooden body and said side wall being extended upward and bent over and downward beyond the top edge of the other side wall forming a top guide plate which slopes from the back forward away from the shuttle eye 105 and from the front backward to a point adjoining the slot in the threader, and means for fastening the threader in place as described.

5. In a shuttle, the combination of a 110 wooden body having a bobbin recess and a threader recess from which a slot and eye extend through the side, with a threader which fits into the threader recess and which has a barrel and vertical side walls of which 115 the side wall adjoining the shuttle eye has a slot which connects with an eye both of which register with the slot and eye in the wooden body and said side wall being extended upward and bent over beyond the 120 top edge of the other side wall forming a top guide plate which slopes from the back forward away from the shuttle eye and from the front backward to a point adjoining the slot in the threader, together with a backward extension of the side wall which has the eye bent at right angles and curved over and down to form a deflector plate, and an extension of the other side wall opposite the deflector plate provided with downwardly 125 130

raking teeth, and means for fastening the threader in place as described.

6. In a shuttle, the combination of a wooden body having a bobbin recess and a threader recess from which a slot and eye extend through the side, with a threader which fits into the threader recess and which has a barrel and vertical side walls of which the side wall adjoining the shuttle eye has a slot which connects with an eye both of which register with the slot and eye in the wooden body and said side wall being extended upward and bent over beyond the top edge of the other side wall forming a top guide plate which slopes from the back forward away from the shuttle eye and from the front backward to a point adjoining the slot in the threader, together with a backward extension of the side wall which has the eye bent at right angles and curved over and down to form a deflector plate with downwardly raking teeth, and an extension of the other side wall opposite the deflector plate provided with downwardly raking teeth, and means for fastening the threader in place as described.

7. In a shuttle, the combination of a wooden body having a bobbin recess and a threader recess from which a slot and eye extend through the side, with a threader which fits into the threader recess and which has a barrel and vertical side walls of which the side wall adjoining the shuttle eye has a slot which connects with an eye both of which register with the slot and eye in the wooden body said side wall being extended upward and bent over forming a top guide plate which slopes from the back forward away from the shuttle eye and from the front backward to a point adjoining the slot in the threader and extends over and beyond the top edge of the other side wall which is curved from each end upward toward a point adjoining the portion of the top guide plate which extends over it, and means for fastening the threader in place as described.

In testimony whereof I hereto affix my signature in presence of two witnesses.

ISAAC SNOW.
